J. E. CANNING.
TOOTH REGULATOR.
APPLICATION FILED JAN. 8, 1917.

1,271,850.

Patented July 9, 1918.

Inventor

John E. Canning.

By *A. J. Board* Attorney

UNITED STATES PATENT OFFICE.

JOHN E. CANNING, OF DENVER, COLORADO.

TOOTH-REGULATOR.

1,271,850.

Specification of Letters Patent.

Patented July 9, 1918.

Application filed January 8, 1917. Serial No. 141,083.

To all whom it may concern:

Be it known that I, JOHN E. CANNING, citizen of the United States, residing at the city and county of Denver and State of Colorado, have invented certain new and useful Improvements in Tooth-Regulators; and I do declare the following to be a full clear, and exact description of the invention, such as will enable others skilled in the art to 10 which it appertains to make and use the same, reference being had to the accompanying drawings, and to the characters of reference marked thereon, which form a part of this specification.

15 My invention relates to improvements in means for regulating or straightening teeth, my object being to provide a device of this character which shall possess a number of advantages over devices intended to 20 accomplish a similar purpose and heretofore known. In these known devices nuts are employed for regulating the arch or arch band, the said nuts being utilized in connection with an anchor bolt or a bolt which 25 is connected with an anchor band, there being one of these bolts and one of these bands at each extremity of the arch.

In my improvement the arch consists of 30 a spiral spring which is wound to form a screw thread, the threads of the arch co-operating with a few interior threads formed in each of the anchor bolts. The spiral spring arch band is preferably so constructed that the portion thereof which 35 engages the threads of one bolt has a right hand thread while the portion thereof in engagement with the other bolt is a left hand thread. The extremities of the arch pass through the bolt which is hollow or 40 consists of a tubular member. By virtue of this construction the arch may be adjusted for tightening or loosening purposes by rotating it since it becomes, in effect, a flexible shaft or spindle. I prefer to fashion 45 the arch band in front or centrally of its length to receive a small wrench or to facilitate the grasping of the same by the use of a pair of pliers for the purpose of rotating the arch. As the arch is rotated it will be 50 understood that such action produces a double effect so far as quickness of adjustment is concerned, since the tightening or lengthening of the band takes place at both extremities where it engages the interior threads of the bolts. Hence, the same ad-

justment is obtained by turning the arch band or by one turning operation, that would be obtained by adjusting a nut at each extremity of the arch band under the old practice. Furthermore, in the old forms of 60 construction it is necessary to locate the nuts and the anchor bands well back in the mouth, thus making it difficult to gain access to these nuts for adjusting purposes; whereas with my improved construction, the 65 part of the arch to which I apply the instrument, as a small wrench or pair of pliers for turning purposes, is located in front where it is easily accessible, thus making the work of adjusting the arch not only much quicker, 70 but much easier as well.

It is evident that in this construction the tubular members which are directly connected with the anchor bands, may be externally screw threaded or not, as may be desired or as circumstances or convenience may dictate.

If desired, the entire arch may be so wound as to make its screw thread uniform throughout its length as a right hand thread. 80 This would be advantageous where it is desired to move the arch lengthwise for the purpose of tooth straightening purposes as where a ligature is connected with a tooth to be treated and it is desired to exert a 85 pulling stress thereon in one direction or the other along the length of the arch. In this case, the entire action will be in one direction and uniform throughout the length of the arch, thus obviating the necessity of adjusting each end separately.

Having briefly outlined my improvement as well as the function it is intended to subserve, I will proceed to describe the same in detail, reference being made to the accompanying drawing in which is illustrated 95 an embodiment thereof.

In this drawing:—

Figure 1 is an elevation illustrating my improvement, the arch band being broken 100 to indicate indefinite length.

Fig. 2 is a fragmentary view of the arch band showing the same so wound that its screw thread is uniform throughout its length.

Fig. 3 is a fragmentary view shown on a larger scale and partly in section, the sectionized part including the hollow anchor bolt and the parts directly connected therewith.

Fig. 4 is a view showing the complete device applied to a set of teeth.

The same reference characters indicate the same parts in all the views.

5 Let the numeral 5 designate an arch band which, as shown in Figs. 1, 3, and 4, consists of two spiral spring members 6 and 7, the member 6 being wound to provide an exterior right hand screw thread while the member 7 is wound to provide an exterior left hand screw thread. These two members 6 and 7 are connected by a part 8 preferably polygonal in cross section and in which the adjacent extremities of the members 6 and 15 7 are anchored. This member 8 may be hollow and the extremities of the members 6 and 7 may be anchored therein in such a manner as to form a continuous passage extending throughout the length of the arch 20 and through which may be passed a stiffening wire 9 which should be composed of spring metal. This spring wire may be advantageously used in connection with the spiral spring arch for reinforcing and tension purposes, since it may be made so small 25 that it will have great resilience and may be bent to correspond with the bending or lateral adjustments of the arch when the latter is connected with the teeth by means of 30 ligatures or other devices.

The object of part 8 is to so shape the arch at its approximate center and at the extreme front of the mouth when the arch is in use to facilitate the rotation of the 35 arch by applying a suitable instrument to the member 8. This member is preferably somewhat larger than the arch and for this reason facilitates the adjustment or rotation of the latter when occasion may require.

40 Each extremity of the arch band enters a tubular member 10 which is shown in the drawing as exteriorly screw threaded as shown at 12 to engage the interior threads of a sleeve 13 of an anchor band 14, the 45 other extremity of the band having a plain or unthreaded sleeve 15 which engages a plain or unthreaded part 16 of the tubular member, one extremity of which is provided with a head or enlargement 17 which forms 50 a shoulder 18 which the sleeve 15 of the anchor band engages. This tubular member is provided with a few interior screw threads as shown at 19, which coöperate with the exterior threads of the spiral spring arch, the balance of the interior of the tubular member being plain or unthreaded as shown at 20. Hence, as the arch 55 is turned, there will be but little resistance where the arch band engages the short interior screw threaded part 19 of each bolt, consequently the extremities of the arch will turn freely in the tubular members while the latter will remain stationary, being held against rotary movement since the resistance to the turning of the tubular members

is much greater than the resistance due to the engagement of the arch band with the few screw threads of these members.

In the form of construction shown in Fig. 2, the arch band 5 consists of a spiral spring 70 which is uniformly screw threaded throughout its length, its central portion being equipped with the member 8 to facilitate rotation and consequent lengthwise adjustment.

75 From the foregoing description the use and operation of my improvement will be readily understood. When the arch with right and left hand threads is used, the anchor bands 14 will be first applied to the back teeth 21 and properly tightened thereon by the adjustment of the tubular members 10 after which the extremities of the arch band will be threaded into the interior screw threaded portions 19 of the tubular 80 members. This adjustment may be quickly effected by rotating the arch whereby double rapidity of movement results as heretofore explained.

85 Having described my invention what I claim is:

1. A tooth regulating device including tubular members an integral part of which is interiorly threaded, and an arch band composed of a flexible member having exterior threads which engage and coöperate with the interiorly threaded portions of the tubular members as the arch band is rotated and anchor bands mounted on said tubular members.

100 2. A tooth regulating device including interiorly threaded tubular members and an arch band composed of a spiral spring whose exterior is screw threaded to coöperate with the interior threads of the tubular members, one part of the arch band having a right hand thread and the other part, a left hand thread.

105 3. A tooth regulating device including an arch band composed of two connected spiral spring members one of which is wound to form a right hand screw thread while the other is wound to form a left hand screw thread.

110 4. A tooth regulating device including an arch band composed of a spiral spring having right and left hand threaded parts, and tubular members having interior screw threads which coöperate respectively with the oppositely threaded parts of the arch, the latter having a part fast thereon between its extremities and fashioned to facilitate the rotation of the arch.

115 5. A tooth regulator of the class described, including anchor bands each of which has a threaded and an unthreaded sleeve, tubular members exteriorly threaded to coöperate with the threads of the sleeves of said bands and shouldered to engage the unthreaded sleeves, and an arch band com-

posed of a spiral spring whose exterior is screw threaded to coöperate with interior threads with which the tubular members are provided, one part of the arch band having a right hand thread and the other part a left hand thread.

6. A tooth regulator including tubular members having interiorly threaded portions, and an arch band comprising a flexible member one end of which is right hand threaded and the other end left hand threaded, said ends engaging the interiorly threaded portions of said tubular members, and means between the extremities of the arch band to rotate the same.

7. A tooth regulating device including

tubular members an integral part of each of which is interiorly threaded, and an arch band comprising a flexible member one end of which has right hand threads and the other end left hand threads, said threads engaging and coöperating with the interiorly threaded portions of the tubular members, and anchor means mounted on said tubular members.
